ARTHUR W. CAPS, OF ROCHESTER, NEW YORK, ASSIGNOR TO PHOTOSTAT CORPORATION,
OF PROVIDENCE, RHODE ISLAND, A CORPORATION OF RHODE ISLAND

SIGNAL FOR PHOTOGRAPHIC APPARATUS

Application filed July 2, 1928. Serial No. 289,761.

This invention relates to the combination with photographic apparatus of signal means for the same, and has for its principal object the provision of such a combination comprising signal means which will inform the operator of the movements of certain mechanism within the photographic apparatus.

Another object of the invention is to provide photographic apparatus having a dark chamber with signal means for indicating the movements of parts within the dark chamber, so coordinated and combined that indication of the signal means may be readily observed outside the dark chamber without transmission of light rays into the same.

Another object is the provision, in photographic apparatus, of a signal which will inform the operator of the approach of sheet conveying means to a sheet holder.

A further object is to provide audible means for notifying the operator that a sheet is about to be withdrawn from the sheet holding means by the conveying means, so that he will know that another sheet may shortly be placed in the holding means.

A still further object of the invention is to provide an audible signal in combination with a dark chamber having a passageway to facilitate passage of sound waves from the signal through a wall of the chamber, the signal being so designed and constructed as to cover the passageway and provide a baffle for preventing passage of light therethrough into the dark chamber.

To these and other ends the invention resides in certain improvements and combinations of parts, all as will be hereinafter more fully described, the novel features being pointed out in the claims at the end of the specification.

In the drawings:

Fig. 1 is a side elevation of one form of photographic apparatus with which the invention may be used, illustrating the present invention applied thereto;

Fig. 2 is a longitudinal vertical section through a part of the apparatus, illustrating details of the invention;

Fig. 3 is an enlarged elevation of one form of signaling means;

Fig. 4 is a section taken approximately on the line 4—4 of Fig. 2, illustrating parts of the signal in elevation, and

Fig. 5 is a transverse vertical section through a part of the signal, taken substantially on the line 5—5 of Fig. 3.

Similar reference numerals throughout the several views indicate the same parts.

The invention is herein disclosed with particular reference to photographic apparatus of the type in which a roll of sensitized sheet material is provided, successive portions of the roll being unwound, exposed, and then severed from the roll. The severed sheets are then placed in suitable holding means such as a chute, from which they are picked up or withdrawn by conveying means and carried to any desired point. During the travel of the sheets they may pass, for example, through developing, fixing, and washing baths, if desired.

The conveying means may include one or more pick-up devices which pass the sheet holding means or chute at intervals. It is desirable that each passage of a pick-up device past the holding means should pick up only one sheet, and in order to insure this, a second sheet should not be fed into the holding means until the previous sheet has been withdrawn. The present invention relates particularly to a signal for informing the operator of the travel of the various pick-up devices which are associated with the conveying means.

The signal may be arranged for example, either at the sheet holding means or chute, or slightly in advance thereof, or even beyond the holding means if desired. No matter in which of these positions it is placed, it is preferably arranged to be actuated by each passage of a pick-up device. The signal may be either visible or audible, and in either case the operator will be notified that a pick-up device is passing, or is about to pass, or has just passed the sheet holding means, depending on which of the three positions mentioned above the signal occupies with respect to the chute.

Preferably the signal is so placed that it is actuated by one pick-up device just as the rear edge of a sheet carried by the next

vious pick-up device passes out of the sheet holding means. In other words, the operation of the signal indicates that the sheet holding means is then clear of a sheet, and 5 the operator may then feed another sheet into the holding means or chute and sever it, without danger of having two sheets in the chute at the same time.

Certain features of the invention are not 10 limited to use for the purpose above described, but may be employed equally well in other situations. For example, the invention 15 contemplates the use of a bell or other suitable audible device as the signaling means, and in 20 case an audible signal is used it is desirable to place openings in the walls of the dark chamber adjacent the signal, in order that the sound waves from the signal may be clearly heard outside of the chamber. The present 25 invention also contemplates, therefore, the provision of an audible signal so designed and constructed as to prevent leakage of light into the dark chamber through the openings or sound passages. It is apparent that this 30 feature of the invention is capable of many different uses, in any form of apparatus in which it may be desired to employ an audible signal within a dark chamber, and it is not limited to use in connection with the sheet holding means and conveying means above mentioned.

One possible form of apparatus with which the invention may be used is shown in side elevation in Fig. 1. On suitable supports 11 35 there may be placed a camera indicated generally by the numeral 12, the camera being provided with a prism 13 for bending the light rays so that the objects to be photographed may be placed upon a horizontal copyholder 14. A roll of sensitized sheet material 15 may 40 be placed within the camera in position so that successive portions may be unwound and placed at 16 in the focal plane of the camera. When a portion of the sheet in the focal plane 45 has been exposed, the sheet may be fed forward the desired amount by feeding means such as the rolls 17, so as to bring a fresh or unexposed portion of the sheet material into the focal plane. The exposed portion of the 50 sheet may then be severed by suitable severing means and may be fed or allowed to drop by gravity into suitable holding means such as the chute 18.

Conveying means, preferably of endless 55 type, may be used to pick up the sheets from the holding means 18 and to convey them to any desired point. This conveying means may comprise a pair of endless members such as the chains 19 (Figs. 1, 2 and 4) which may 60 be spaced from each other in a direction transversely of the apparatus and may carry one or more pick-up devices such as the bars 20, extending across from one of the conveyor chains to the other, one end of each bar being 65 attached to each chain.

Each of these cross bars 20 may carry one or more forwardly extending pins or darts 21, which are adapted to pierce the sheet 22 (Fig. 2) held within the holding means 18 as the pick-up device travels past this holding 5 means, the sheet thus becoming attached to the conveying means so that it is withdrawn from the holding means and carried along by subsequent movement of the conveyor. The path of travel may pass through a tank 25, 10 shown in Fig. 1, which may be divided into sections or compartments containing developing, fixing, and washing baths, so that the sheet material may be treated during its passage. Any suitable means may be employed 15 for removing the sheet from the conveyor at any desired point, the removal preferably taking place over the tank 26 so that the sheets when removed will drop into this tank, from which they may be taken as desired by the 20 operator.

The conveying means may be driven either intermittently or continuously by any suitable mechanism such as the motor 27, shown in Fig. 1. Whether the driving be intermittent or continuous, it will be apparent that in either case a pick-up device such as the bar 20 will travel past the holding means 18, and after an interval of time another pick-up device will likewise travel past the holding 30 means. After each passage of a pick-up device, it is apparent that the sheet occupying the chute prior to such passage will have been removed therefrom, and another sheet may then be placed in the chute in position to be 35 picked up by the passage of the next succeeding pick-up device.

If a sheet has been placed in the chute and has not yet been removed therefrom by the conveyor, a second sheet should not be placed 40 in the chute because it would be picked up at the same time as the first sheet, and when two sheets are picked up together they lie in contact with each other throughout their travel, so that one of the sheets is apt to be imperfectly treated. It is, therefore, important 45 that the operator be notified of the successive passage of the pick-up devices past the chute, so that he will know when a sheet previously placed in the chute has been picked up and 50 when it is safe to place another sheet therein.

The means for notifying the operator, in the present instance, may comprise an audible signal such as the bell 30, illustrated in Figs. 2 to 5. This bell may be mounted by 55 means such as a screw 31 on a support which comprises radially extending arms 32 attached to the top of an upstanding annular flange 33 having a flat marginal flange 34 surrounding it, as shown most clearly in Fig. 60 5. The marginal flange 34 is widened at one point as at 35, and on this widened portion there may be mounted a screw 36 which serves as a pivot for a sleeve 37 carrying a bell clapper arm 38 provided with a clapper 65

39. A spring 40 urges the clapper arm against the stop pin 41. As shown in Fig. 3, the clapper 39 is out of contact with the bell 30 when the clapper arm is against the stop member, but it will be understood that a portion of the clapper arm is resilient so that the clapper may hit the bell when the arm has been displaced and is drawn back rapidly against the stop 41 by the spring 40.

10 Operating means for the clapper may include an arm 42 attached to the sleeve 37, this arm extending up alongside one of the conveyor members 19 in the path of travel of the cross bars 20, so that the arm 42 is displaced and swung in counter-clockwise direction, when viewed as in Figs. 2 and 3, at each passage of a pick-up device or cross bar 20. Thus the bell is operated each time a pick-up device passes it.

20 In the present instance, the signal bell is shown as being mounted on the inner side of a wall 45 of the dark chamber, at a point slightly in advance of the sheet holding means or chute 18. That is to say, the pick-up devices pass and actuate the signal slightly before they reach the holding means.

In order that the signal shall be distinctly audible outside of the dark chamber, and preferably at some distance from the apparatus, openings 46 are provided in the wall 45, these openings all being within that portion of the wall which is surrounded by the flange 33. It will be noted from Fig. 5 that the flange 33 extends close to the marginal portion of the bell 30, and overlaps the edge of the bell a substantial distance.

By the use of this construction, it is found that the flange 33 and the bell 30 together constitute means for preventing light from entering the dark chamber through the openings 46. It will be noted that there is no direct path in which light can travel from any of the openings 46 to the interior of the dark chamber, and as the interior surface of the bell 30 and the surfaces of the flange 33 are preferably given a dull finish, it follows that no appreciable amount of light can be reflected back and forth so as to enter the dark chamber through the labyrinth-like space between the bell and the protecting flange 33. In this way, fogging or other damage to the sensitized sheet material within the dark chamber is prevented, although openings are provided for allowing the free passage of sound waves from the audible signal within the dark chamber to points outside of the chamber.

In operation, the pin bar 20 shown near the top of Fig. 2 travels past and actuates the clapper operating arm 42 just at the instant that the previous pin bar (not shown) in advance of the one mentioned is moved to such a position that the rear edge of the sheet which it has picked up and withdrawn from the chute is just leaving the chute. The in-

stant the signal operates, therefore, the operator knows that the chute 18 has been cleared of the previous sheet, and he, therefore, operates the necessary mechanism to feed the next section of the sheet material downwardly past the feed rollers 17 into the chute 18, and severs it.

The conveying means is driven at such a rate of travel that there is ordinarily sufficient time for this feeding and severing operation to take place after the actuation of the signal before the pin bar 20 which actuated the signal reaches the chute 18. By the time the pick-up device or pin bar reaches the chute, there is, therefore, a sheet 22 present in the chute as shown in Fig. 2. The pins 21 on the pick-up device pierce this sheet as the pick-up device travels past the chute and draw this sheet out of the chute. Just as the rear edge of the sheet is passing out of the end of the chute, the next succeeding pick-up device or pin bar 20 passes and actuates the clapper operating arm 42 so that the bell rings again and indicates to the operator that he may wind down or feed another sheet. In this way, only one sheet at a time is placed in the holding means or chute and there is no danger of two sheets being picked up by a single pick-up device.

While one embodiment of the invention has been disclosed, it is to be understood that the inventive idea may be carried out in a number of ways. This application is therefore not to be limited to the precise details shown, but is intended to cover all variations and modifications thereof falling within the spirit of the invention or the scope of the appended claims.

I claim as my invention:

1. The combination with a photographic apparatus having a dark chamber and sheet handling means therein, of audible signal means located within said dark chamber for indicating the position of a part of said sheet handling means, and an opening in a wall of the dark chamber for transmitting sound from said audible signal means exteriorly of said chamber, said opening being covered by said signal means so that light from said opening is thereby excluded from said dark chamber.

2. The combination with a photographic apparatus having a dark chamber and a member movable therein, of audible signal means located within said dark chamber and operable by said member, and an opening in a wall of said dark chamber for transmitting sound from said audible signal means exteriorly of said chamber, said signal means comprising baffle means for excluding light from said dark chamber.

3. The combination with a photographic apparatus having a dark chamber, of an audible signal within said chamber, an opening in a wall of said chamber adjacent said signal for passage of sound waves from within

said chamber to points exteriorly thereof, and baffle means adjacent said opening for excluding light from said dark chamber.

4. In a photographic apparatus, the combination with sheet holding means, of sheet conveying means having a portion arranged to pick up a sheet from said holding means, and audible signal means operated automatically by the movement of said pick-up portion for signaling the approach of said portion to said holding means.

5. In a photographic apparatus, the combination with sheet holding means, of sheet conveying means including a plurality of spaced pick-up portions each arranged to travel past said sheet holding means and to pick up a sheet held thereby, and a signal for indicating the approach of each of said pick-up portions to said holding means, said signal comprising a bell and a clapper having a clapper operating arm extending into the path of travel of each of said pick-up portions.

6. In a photographic apparatus, the combination with a dark chamber adapted to hold sensitized sheet material, of a member movable within said chamber, an audible signal within said chamber operated by movement of said movable member, an opening in a wall of said chamber adjacent said signal to assist passage of sound waves from said audible signal to points outside of said chamber, and means preventing leakage of light from said opening into said chamber.

7. In a photographic apparatus, the combination with a dark chamber adapted to hold sensitized sheet material, of a member movable within said chamber, a signal bell within said chamber, said bell including a marginal flange, a bell clapper operated by movement of said movable member, an opening in a wall of said chamber adjacent said bell to assist passage of sound waves from said bell to points outside of said chamber, and a flange on said wall surrounding said opening and extending into close proximity to the marginal flange on the bell, for preventing leakage of light from said opening into said chamber.

8. In a photographic apparatus, the combination with a dark chamber adapted to hold sensitized sheet material, of a member movable within said chamber, a signal bell within said chamber, said bell being cup-shaped and being mounted on a wall of said chamber with its concave side toward said wall, a bell clapper operated by movement of said movable member, an opening in said wall of said chamber within the area covered by said bell to assist passage of sound waves from said bell to points outside of said chamber, and a flange on said wall surrounding said opening and overlapping the edge of said bell and extending into the concave por-

tion of said bell, said flange serving to prevent leakage of light from said opening into said chamber.

9. In a photographic apparatus, the combination with a dark chamber, of sensitized sheet holding means therein, sheet conveying means including a pick-up portion arranged to travel past said sheet holding means and to pick up a sheet held thereby, and a signal for indicating the approach of said pick-up portion to said holding means, said signal including a cup-shaped bell mounted on the inner side of a wall of said chamber with its concave side toward said wall, a bell clapper operated by movement of said pick-up portion, an opening in said wall of said chamber within the area covered by said bell to assist passage of sound waves from said bell to points outside of said chamber, and a flange on said wall surrounding said opening and overlapping the edge of said bell and extending into the concave portion of said bell, said flange serving to prevent leakage of light from said opening into said chamber.
